UNITED STATES PATENT OFFICE

1,960,951

METHOD OF CONVERTING BY CATALYSIS
MINERAL AND VEGETABLE OILSRené Oppenheim, Gennevilliers, France, assignor
to Société Anonyme le Carbone, Gennevilliers,
FranceApplication February 17, 1932, Serial No. 593,690
In France January 22, 1932

3 Claims. (Cl. 196—52)

- This invention relates to an improvement in or modification of the process set forth in the specification of the patent of F. C. F. Portail, No. 1,842,197 bearing the date of January 19, 1932.
- 5 The invention forming the subject matter of said parent patent of Portail consists in the conversion of mineral and vegetable oils in order to obtain lighter products, by catalysis by the action of activated carbon.
- 10 It is indicated in the specification of the patent of Portail that it is advantageous to agglomerate the activated carbon into blocks through which the oils that are to be converted are passed, the said blocks being, if required, pierced by channels.
- 15 The subject matter of the present application is an improvement in the aforesaid process, which consists essentially in forming the catalyst of an entanglement or a fabric of carbonized fibres.
- 20 By way of example, there may be mentioned as suitable for the new use the carbonized fabric of lamp wick or carbonized cotton wool.
- In order to improve the quality of the product and so render more effective the decomposition 25 of the hydrocarbons on which it is to act, the product is treated in accordance with the known activation processes in order that the carbon of which it is formed may be activated. But first cotton or other such fibers are connected by matting them into a sort of wool or else weaving the same together to form a fabric, either form being later carbonized and activated.
- 30 This product may be used either alone or combined with a suitable support, upon which it may be spread, wound, etc. It may also be provided with a reinforcement to support it. A characteristic method of applying the reinforcement consists in incorporating it intimately in the product, for example by introducing it into the product during the preparatory matting or weaving. It is thus possible to employ at the same time in the weaving threads that are to be carbonized and other threads of products which do not carbonize and which subsequently form the reinforcement of the fabric.
- 35 The single figure of the drawing illustrates in section and only by way of example a vertical cross-section of an installation for carrying out the process according to the invention.
- 40 The reservoir *b* contains the oil to be treated. A compressor *a* is connected to the upper portion of reservoir *b* and creates an air pressure therein. A pipe *b'* is connected between the conical bottom of said reservoir *b* and a header *c'*.
- 45 One or more reaction tubes or chambers simi-
- lar to *c* are disposed within the heating chamber *d* and are heated by a plurality of burners *e*, said reaction tubes *c* are located and connected in parallel between headers *c'* and *c''*, all mounted within heating chamber *d*, and which on such form has to increase in section toward the cylinder *c''*. Each member *c* contains a felted or woven mass of carbonized and activated fibres which of course increase in section toward header *c''* as said mass fills the interior of such member *c*. The output of such tubes or chambers which are a hundred millimeters in diameter is approximately fifty or more liters per hour each, the reaction tubes *c* forming catalyzing chambers due to the presence of the fibrous activated carbon *f*.
- 55 The treated liquid is conducted by a pipe *g'* from the header *c''* into a pressure reducing chamber *g*, from whence the light products are conducted through the coil of a condenser *h* into a receptacle *i*. The non-condensable constituents of the oil are discharged by a pump *j* to be used in appropriate manner.
- 60 The fibrous activated carbon may be manufactured according to known methods which are not necessarily in themselves part of the invention, but the following methods for preparing such product may be noted.
- 65 The fibrous product may initially be in the form of a strip wound on a core of carbon for example, or on an end of a tube etc., so that the whole, after winding, forms a block; the roll formed may then, if desired, be enclosed in a metallic box. The strip may also be arranged as a flat coil. It is also possible to replace it by a pile of discs or rings.
- 70 The practical embodiment may consist of a simple pile of pieces of cotton wool activated in a tube; this enables a uniform mass of entangled fibres to be obtained.
- 75 The block or mass of carbonized fibres formed as just described is placed in a suitable envelope and is supported by its reinforcement or by any suitable means, for example by plates of porous carbon, by metallic pieces, etc.
- 80 The activated carbon formed as just described presents special advantages. The activated cotton wool or fabrics have a porosity which is very superior to that of the agglomerated blocks described in the patent of Portail. A column of cotton wool or of fabric arranged in a pipe causes a loss of pressure that is much smaller than that caused by a solid block of activated carbon.
- 85 Moreover, owing to the very great plasticity of the activated cotton wool, it is possible to
- 90
- 95
- 100
- 105
- 110

regulate very efficaciously the porosity of the layer of carbon and, consequently, the period of contact between the liquid to be treated and the active carbon.

- 5 Finally, the great plasticity of the activated cotton wool enables the interstices, through which the liquid to be treated could flow away without being absorbed by the carbonized and activated cotton wool, to be eliminated by a 10 suitable heaping thereof in the vessel in which the treatment is to be carried out. There is thus ensured an intimate contact between the liquid to be treated and the catalyst, which enables the yield of the operation to be considerably 15 improved.

The manner of using the apparatus already described in order to carry out the process may be varied according to the oils which are to be treated and according to certain laboratory tests 20 which have already been indicated in the above mentioned patent of Portail and given by way of example below:

By passing gas oil containing 75% of products distilling above 250° C. through the activated 25 carbon, it was found that decomposition took place as soon as the temperature of the catalyzer reached 300° C.

At 350° C. there were obtained about:

35% of combustible gases (gas with a great 30 calorific power of 15,000 calories per cubic meter approximately).

The liquid residue (65%) subjected to fractionated distillation gave:

35 6% spirit at temperatures up to 110° C.
6% spirit at temperatures from 110 to 150° C.
9% spirit at temperatures from 150 to 200° C.,
and
20% liquid at temperatures from 200 to 250° C.

40 That is to say a total of 76% of products distilling below 250° C. were obtained.

When the temperature was raised to 450° C. there were produced:

45 35% approximately of combustible gas (of great calorific power, of 15,000 calories approximately per cubic meter).

50 10% spirit at temperatures below 110° C.
8% spirit at temperatures from 110 to 150° C.
10% spirit at temperatures from 150 to 200° C.,
and
20% spirit at temperatures from 200 to 250° C.
or a total of 85% of products distilling below 250° C.

55 In both cases the final liquid residue, that is to say,

24% in the first case and
17% in the second

60 may be passed again over the activated carbon and again furnish light volatile spirits. The final results after this second passage comprise 90% of products distilling below 250° C.

65 Actual tests also indicate that vegetable oils may be cracked by passing the same through felted or woven fibrous activated carbon. The results of a test on peanut oil follow:

100 c. c. of peanut oil were passed through activated carbon and the following results of fractionated distillation were obtained:

	c. c.
Gas, non-condensable at 0° C.	20.2
Liquid	53.0

of which 18 c. c. distill under 150° C., 14 c. c. distill between 150° and 235° C. and 21 c. c. do not distill at 235°.

The different figures given above are, as will be understood, merely given by way of an indication and will vary according to the nature of the product treated, the speed of passage of this product, the cooling temperature of the products distilled and, finally, the nature of the activated carbon used as catalyst, which is here a felted or woven fibrous mass.

It is furthermore remarked that the gas obtained may be used for any suitable purposes and in particular for heating the activated carbon and the fractionated distilling apparatus.

The arrangements described above are only given by way of example; all the details of performing the new improvement and of carrying it into effect may be varied without changing the principle of the invention.

Having now fully described my invention and indicated a practical manner of carrying the same out in practice, I claim:—

1. Process for catalytically transforming or converting mineral and vegetable oils, which consists in exposing the same at an elevated temperature ranging from about 300° to about 350° to the action of activated carbon in the form of entangled and interlocated fibres of vegetable origin suitably carbonized and activated, which are distinct, long, flexible and resistant so as to constitute in their aggregate, a highly porous mass of changeable and plastic form.

2. Process for catalytically transforming or converting mineral and vegetable oils, which consists in exposing the same at an elevated temperature ranging from about 300° to about 350° to the action of activated carbon in the form of entangled, interlaced and felted carbonized fibres of vegetable origin such as, suitable carbonized and activated cotton wool, which carbonized fibres are distinct, long, flexible and resistant so as to constitute in their aggregate, a highly porous felted mass of changeable and plastic form.

3. Process for catalytically transforming or converting mineral and vegetable oils, which consists in exposing the same at an elevated temperature ranging from about 300° to about 350° to the action of activated carbon in the form of entangled, interlaced and woven carbonized fibres of vegetable origin such as a wick of cotton fabric, suitably carbonized and activated, which carbonized fibres are distinct, long, flexible and resistant so as to constitute in their aggregate, a highly porous mass of changeable and plastic form.

RENE OPPENHEIM.
